UNITED STATES PATENT OFFICE.

PERRY B. TURNER, OF KING, NORTH CAROLINA.

AIR-HEATING FURNACE.

Application filed January 13, 1923. Serial No. 612,486.

To all whom it may concern:

Be it known that I, PERRY B. TURNER, a citizen of the United States, residing at King, in the county of Stokes and State 5 of North Carolina, have invented certain new and useful Improvements in Air-Heating Furnaces, of which the following is a specification, reference being had to the accompanying drawings.

- 10 This invention relates to certain improvements in air heating furnaces and has relation more particularly to a device of this general character especially designed and adapted for use in the drying of tobacco
- 15 or the like and it is an object of the invention to provide a furnace of this general character with novel and improved means whereby a blast of air heated to a relatively high temperature may be discharged
- 20 in a manner which best complies with the requirements of practice.

Another object of the invention is to provide a novel and improved device of this general character comprising a body divided 25 horizontally to produce vertically spaced compartments the upper compartment constituting an air chamber and the lower compartment constituting a fire box together with means associated with the air chamber 30 for drawing air therethrough to be heated and to discharge such heated air in a forced draft.

An additional object of the invention is to provide a novel and improved device of 35 this general character comprising a body divided into an upper compartment and a lower compartment, the partition dividing said compartments being a high conductor of heat, the upper compartment having an induction opening in the side thereof and eduction means at the end thereof but remote from the induction opening, the lower compartment constituting a fire box.

Another object of the invention is to provide a novel and improved device of this 40 general character comprising an air chamber and a fire box positioned therebelow, the air chamber being provided with an induction opening and an eduction means and 45 wherein the induction opening has associated therewith means to prevent entrance of smoke from the fire box entering the air chamber.

The invention consists in the details of 50 construction and in the combination and ar-

rangement of the several parts of my improved air heating furnace whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the 65 better understood, I will now proceed to describe the same with reference to the accompanying drawings, wherein:

Figure 1 is a view in top plan but of somewhat a diagrammatical character illustrating a furnace constructed in accordance with an embodiment of my invention and in applied relation in connection with a tobacco drying plant or the like;

Figure 2 is a fragmentary vertical sectional view taken through the structure as illustrated in Figure 1;

Figure 3 is a view in perspective of my improved furnace as herein disclosed; and

Figure 4 is a transverse sectional view 80 taken through the device as illustrated in Figure 3.

As disclosed in the accompanying drawings, F denotes my improved furnace which comprises the side walls 1 preferably of 85 brick and of a desired height. Bridging the space between the walls 1 and at a point substantially midway the height thereof is a partition 2. The partition 2 is preferably of sheet iron and is supported by said side 90 walls. This partition 2 provides the upper or air chamber A and the lower chamber or fire box B.

One end of the fire box B is closed by the wall 3 while the opposite end 4 is open. 95 The open end 4 provides means whereby the necessary fuel may be readily placed within the fire box and also permits the requisite entrance of air to properly support combustion.

The end of the chamber A immediately adjacent to the open end 4 of the fire box B is closed by the wall 5. The opposite end portion of the chamber A is gradually reduced in width and terminates in an eduction portion 6. This opening 6 is directly in communication with a conduit 7 closed at its top and extending downwardly. Leading from the lower portion of the conduit 7 is a pipe 8 which extends within the 110

barn X or otherwise and as herein disclosed this pipe 8 has extending therefrom in opposite directions the branches 9 terminating in the discharge openings 10. The pipe 8 and branches 9 are preferably underground with the discharge ends of the branches 9 substantially flush with the ground level. If preferred a suitable protecting guard 11 or the like may be disposed over the discharge ends of the branches 9 to prevent entrance of dirt or other foreign matter.

A side wall 1 at a point in close proximity to the closed end 5 of the chamber A is provided with an induction or air inlet opening 12. Extending through the upper portion of the conduit 7 is a fan shaft 14, said shaft extending beyond the opposite sides of said conduit and being rotatably supported by bearings 15 which are exteriorly located so as not to be subjected to the heated air passing from within the chamber A through the conduit 7. Any means may be employed for rotating the fan, though such is not illustrated.

Fixed to the shaft 14 and working within the top of the portion 6 is a fan 16 which operates to draw air through the chamber A and discharge such air under forced draft through the conduit 7, the pipe 8 and the branches 9 so that the interior of the barn X or the like will be heated to a relatively high temperature or a temperature sufficient to properly dry out tobacco or the like.

The air as it passes through the chamber A is particularly heated by contact with the partition 2, said partition being directly subjected to the heat of the fire burning within the fire box B. In practice I find it of advantage to hold a fire within the box B sufficient to maintain the partition 2 substantially at a red heat because under this condition it has been fully demonstrated in practice that the air discharged within the barn X or the like is of a temperature to best accomplish the results desired.

Leading from the fire box B at a point in close proximity to its inner or closed end is a flue 17 whereby the requisite draft is effected to maintain the fire within the box B and carry off the products of combustion.

Sometimes it occurs that smoke and other products of combustion pass out of the front or open end 4 of the box B. To prevent such smoke or products of combustion from entering within the chamber A I find it of advantage to provide the outstanding and laterally disposed wing or baffle 18 which

is arranged in advance of and close to the induction or air inlet opening 12.

The top 19 of the furnace may be of any preferred material such as a concrete or stone slab or any other material which can be employed with advantage.

From the foregoing description it is thought to be obvious that an air heating furnace constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A furnace comprising a body including a top, side and end walls, a horizontal partition extending throughout the length and width and dividing the interior into a lower compartment constituting a fire box and an upper compartment constituting an air chamber, the end wall being omitted below said partition at one end only to provide a stoking opening for the fire box, an outlet flue communicating with the other end of the fire box, one side wall of the air chamber having an air inlet opening, the other end of the air chamber being constricted, a conduit at and communicating with said constricted end and extending downwardly, an outlet pipe leading from said conduit, and blast producing means at the juncture of the constricted end with the conduit.

2. A furnace comprising a hollow body, a horizontal partition extending throughout the length and width thereof and dividing the interior into a fire box and an air chamber, one end of the fire box being open and the opposite end of the air chamber being open, an outlet conduit leading from the open end of the air chamber, an outlet flue leading from the closed end of the fire box, said air chamber having an air inlet opening at the open end of the fire box, and a laterally extending wing at the open end of the fire box for preventing passage of smoke into said air inlet opening.

In testimony whereof I hereunto affix my signature.

PERRY B. TURNER.
